DESIGN FOR A BOTTLE

Lawrence J. Kihn, Pittsburgh, Pa., assignor to J. T. & A. Hamilton Company, a corporation of Pennsylvania

Application July 10, 1934, Serial No. 52,520

Term of patent 14 years

To whom it may concern:

Be it known that I, LAWRENCE J. KIHN, a citizen of the United States, residing at Pittsburgh, in the county of Allegheny, and State of Pennsylvania, have invented a new, original, and ornamental Design for Bottles, of which the following is a specification, reference being had to the accompanying drawing, forming part thereof, Figs. I, II, and III are views in rear, in front, and in side elevation of a bottle embodying my new design.

I claim:

The ornamental design for a bottle, as shown.

LAWRENCE J. KIHN.
